UNITED STATES PATENT OFFICE.

CHARLES B. REYNOLDS, OF SAWTELLE, CALIFORNIA.

DESIGN FOR AN AUTOMOBILE-TIRE.

50,360.

Specification for Design.

Patented Feb. 20, 1917.

Application filed January 13, 1917. Serial No. 142,329. Term of patent 3½ years.

To all whom it may concern:

Be it known that I, CHARLES B. REYNOLDS, a citizen of the United States, residing at Sawtelle, in the county of Los Angeles and State of California, have invented a new, original, and ornamental Design for Automobile-Tires, of which the following is a specification, reference being had to the accompanying drawing, forming part thereof.

Figure 1 is a fragmentary plan view of the tire tread, showing my new design, and

Fig. 2 is a transverse sectional view through the tire, showing my new design.

I claim:

The ornamental design for an automobile tire, as shown.

CHARLES B. REYNOLDS.
